UNITED STATES PATENT OFFICE.

SAMUEL SEGAL, OF NEW YORK, N. Y., ASSIGNOR TO BURGLAR PROOF LOCK AND HARDWARE CORPORATION, OF NEW YORK, N. Y., A CORPORATION OF NEW YORK.

DESIGN FOR A LOCK-CASING.

• 50,286.

Specification for Design.

Patented Feb. 6, 1917.

Application filed December 11, 1914. Serial No. 876,738. Term of patent 14 years.

To all whom it may concern:

Be it known that I, SAMUEL SEGAL, a citizen of the United States, and a resident of the city of New York, Middle Village, borough of Queens, in the county of Queens and State of New York, have invented a new, original, and ornamental Design for Lock-Casings, of which the following is a specification, reference being had to the accompanying drawings, forming part thereof.

Figure 1 is a front perspective view of a lock casing; and

Fig. 2 is a rear perspective view, showing my new design.

I claim:

The ornamental design for a lock casing, as shown.

SAMUEL SEGAL.
